UNITED STATES PATENT OFFICE.

JOHN C. DEHLS, OF BROOKLYN, NEW YORK, ASSIGNOR TO NATIONAL PNEUMATIC ACTION CO., INC., OF NEW YORK, N. Y., A CORPORATION OF NEW YORK.

AUTOMATIC MUSICAL INSTRUMENT.

1,208,755.

Specification of Letters Patent. Patented Dec. 19, 1916.

Application filed December 12, 1913. Serial No. 806,138.

To all whom it may concern:

Be it known that I, JOHN C. DEHLS, a citizen of the United States, and a resident of Brooklyn, in the county of Kings and State of New York, have invented certain new and useful Improvements in Automatic Musical Instruments, of which the following is a specification.

The invention pertains more particularly to accenting devices with the use of which a note or notes played on an automatic musical instrument having a traveling perforated music sheet may be accented during the travel of the sheet.

15 My invention contemplates the automatic accenting of the notes during the travel of the perforated sheet from one spool to another, and in carrying out my invention I provide in connection with the pneumatic mechanism a pivoted or hinged bar or frame made hollow in its end portions so as to communicate with the pneumatic features of the piano and extending transversely across the outer face of the music sheet and pressing 20 the latter lightly against the tracker bar, said pivoted or hinged frame having in its hollow end portions perforations in line with the accenting perforations in the music sheet, and the tracker bar at its end portions having 25 openings which become uncovered as the accenting perforations in the sheet pass by them and when so uncovered admit atmospheric air to the interior of said pivoted or hinged frame to travel through special 30 mechanism to the main bellows chest for accenting the notes created at the same time by the perforations in the music sheet passing over the regular perforations in the tracker-bar.

35 The invention will be fully understood from the detailed description hereinafter presented, reference being had to the accompanying drawings, in which:

Figure 1 is a front elevation, partly in section and partly broken away, of a piano player embodying the features of my invention, the parts being shown in the normal position they occupy during the playing of soft music; Fig. 2 is an enlarged vertical section on the dotted line 2-2 of Fig. 1, through the music-box of the piano player; Fig. 3 is an end view of the same taken from the right hand end of Fig. 1; Fig. 4 is a detached front elevation of a portion of the 50 tracker-bar, and Fig. 5 is a detached rear

view, partly broken away and partly in section, of the pivoted or hinged frame which during the employment of the invention engages the traveling sheet along the longitudinal center line of the tracker-bar, Fig. 5 60 being presented to show the openings in the rear side of the end portions of said frame and also the means by which communication between the end portions of said frame is prevented.

65 In the drawings, 10 designates a customary form of roll box adapted to support a tracker-bar 11, a music spool 12 and a take-up spool 13 to receive a music sheet 14 as unwound from the spool 12 and to permit the 70 rewinding of said sheet on said spool 12 when the latter is to be removed from the frame or box 10. The means for rotating the spools 12, 13 are well known in the art and have not therefore been illustrated, my 75 invention not pertaining to the shifting gears or other like parts of a piano player. The spool 12 has a socket at one end to receive the usual spring pressed spindle 15, and at its other end said spool is detachably 80 keyed to the inner end of a spindle 16 mounted in a bearing 17 in the vertical side of the box or frame 10. The tracker-bar 11 is mounted between the sides of the box 10 and is of ordinary character, except, in this 85 instance, I provide near each end thereof an opening 18 which constitutes a part of the accenting features of the invention, said openings 18 extending transversely through said bar and being permanently open at 90 their inner ends and permanently closed at their outer ends by the music sheet 14, except when the special accenting perforations 19 along the edges of said sheet pass into register with said openings 18. There is an 95 opening 18 near each end of the tracker bar 11 and a series of the accenting perforations 100 19 in the music sheet adjacent to each edge of the latter for passing into register with said openings 18 from time to time as occasion may require, the perforations 19 in the sheet being in horizontal alinement with the regular perforations in the sheet representing notes to be accented on reaching the tracker bar.

105 Between the sides of the roll box 10 and journaled in said sides so as to be capable of a hinged movement, I mount a frame (numbered as a whole 20) composed of two side members 21, 22 and a horizontal mem- 110

ber 23 connected with said side members and carried thereby, said member 23 being adapted to engage the music sheet 14 in line with the openings in the tracker bar and 5 lightly, but firmly, press said sheet against the face of said bar. The side members 21, 22 of the frame 20 are hollow and have rectangular portions at their lower ends extending through bearings in the sides of the box 10 and respectively connected with conduits 24, 25 to be hereinafter referred to, said conduits being flexible so that the frame 20 may be conveniently turned upwardly against the traveling sheet 14, as 10 shown in Figs. 1 and 2, or downwardly therefrom, as may be desired. The frame 20 constitutes one of the important features of my invention, although the invention is not limited to the specific form of frame 15 shown. The horizontal member 23 of the frame 20 is provided on its rear face in close proximity to the edges of the traveling sheet 14 with small apertures or air inlet openings 26, 27, which when said member 23 is in its upper position are in line with the openings 18 in the tracker bar 11 and in the vertical plane of the accenting openings 19 in the music sheet 14. The openings 26, 27 in the member 23 of the frame 20 are closed from communication with the openings 18 in the tracker bar 11 by the music sheet 14, except when the openings 19 in said sheet pass into register with said openings 26, 27, and at that time there 20 is a clear passage for atmospheric air through the openings 18 in the tracker bar, perforations 19 in the sheet and apertures 26, 27 in the aforesaid member 23, the air being thus permitted to enter said member 25 and travel downwardly through the side members 21, 22 of the frame 20 and into the conduits 24, 25, whence the air passes to the other portions of the mechanism, as will be explained hereinafter. A perforation 19 at each end of the sheet may at the 30 same time pass into register with the openings 18 in the tracker bar and the apertures 26, 27 in the frame 20, and under such circumstances the bass and treble notes may both be accented, but since the member 23 of the frame 20 has its side members 21, 22 partitioned off from each other, either an accenting perforation 19 for the bass or an accenting perforation 19 for the treble 35 50 may pass into register with one of the openings 18 in the tracker bar and one of the openings in the frame 20, and under such circumstances the atmospheric air would flow only through one side of the frame 20 and only the one note, either bass or treble, as the case might be, will be accented.

The turn-buckle or nut 29 connecting the two members of the frame 20 permits of the lateral adjustment of said members 55 from or toward each other for the purpose

of adjusting the same and the openings 26, 27 therein with relation to the openings 18 in the tracker-bar and perforations 19 in the music sheet. The two side members or sections of the frame 20, while hollow, are separated from each other, so far as air communication is concerned, by means of internal plugs 28 (Fig. 5) as well as by the turn-buckle or nut 29, it being the intention that each end portion of said frame shall act independently of the other in effecting the accenting. I provide the frame 20 with a spring 30 which may serve to press the upper portion or member 23 of said frame against the traveling sheet 14 at the horizontal center line of the tracker-bar 11, said spring 30 also, when the frame 20 is turned outwardly and downwardly from its operative position shown in Fig. 2, acting to hold said frame in its then lower position. The frame 20 will be held in its upper position during the travel of the music sheet 14, and may be turned to its lower position when it is desired to rewind said sheet upon the spool 12 and place a further music sheet 30 within the box 10.

The frame 20 may be moved to its operative and inoperative positions by hand, but in the present instance I have provided a pneumatic 31 by means of which said frame 20 may be moved automatically, said pneumatic 31 having at its hinged side an arm 32 pivotally connected with a rack-bar 33 in mesh with a gear wheel 34 secured on a horizontal member of the frame 20. In Fig. 3 I illustrate the rack bar 33 and gear wheel 34 as having been operated rearwardly by the vacuum in the pneumatic 31 to turn the frame 20 to its operative position, and by the arrow shown in Fig. 3 I indicate the movement that the gear wheel 34 will have when atmospheric air is admitted to the pneumatic 31 and the latter opens to move the rack bar 33 forwardly for the purpose of turning the frame 20 forwardly and downwardly from the traveling sheet 14. I may employ the pneumatic 31, arm 32, rack-bar 33 and gear wheel 34 for effecting the automatic movement of the frame 20, and in such employment the spring 30 is also an advantage in that it assures a uniform engagement of the teeth of the gear wheel 34 with the teeth of the rack bar 33 and an even uniform movement of the frame 20 without undue freedom of the moving parts which 110 might cause a rattling noise or be otherwise objectionable. While I prefer to employ automatic means for moving the frame 20 from one to the other of its two positions, it is perfectly obvious that said 115 frame may be operated by the hand and that under such condition the spring 30 is useful in binding the frame 20 in each of said positions. The hinged or movable side of the pneumatic 31 is connected with a spring 35 130

whose normal tendency is to move said side to its open position and cause the rack bar 33 to turn the frame 20 to its lower or inoperative position. A tube 36 communicates with

5 the interior of the pneumatic 31.

In the construction of the instrument care should be taken to see that the horizontal member 23 of the frame 20 does not interfere, when in its operative position, with

10 the entrance of air into the ordinary tracker bar ducts to operate the music pneumatics. The member 23 being circular in cross-section has only a line contact with the traveling perforated sheet, and hence

15 will not stop the passage of air into the ordinary tracker bar ducts unless said member is of undue diameter or said ducts of very small diameter. The entrances to the ducts and the diameter of the member 23 should

20 be such that said member when in its operative position will not prevent the entrance of air into said ducts.

In the operation of a musical instrument employing my invention, vacuum is created in the player action to permit the player to work, as in playing, as usual; and this vacuum acts through the tube 36 to close or collapse the pneumatic 31 in opposition to the force of the spring 35 and effect, through the rack bar 33, the movement of the frame 20 to its operative position. On re-rolling the music sheet on the instrument, vacuum communication is cut off from the action, as customary in all

35 usual players, and this will have the effect of cutting off the vacuum from the pneumatic 31 and permitting the spring 35 to, through the hinged side of the pneumatic, arm 32, rack bar 33, and gear wheel 34, move the

40 frame 20 to its lower or inoperative position.

In the drawings, 37 denotes the usual main bellows chest within which the requisite vacuum is created, 38 the usual pumps, 45 and 39 the action chest, which is subdivided into chambers 40, 41 by means of a central partition 42. Upon the bellows chest 37 are, at each end thereof, an auxiliary chest 43 separated into two divisions by a partition 44, one division 45 being in communication

49 through a port 46 with the said bellows chest and through a port 47 with a pneumatic or bellows 48, said port 47 being in one wall of the bellows and the other or

55 hinged wall of the bellows having a pad 49 by which the port 47 may be partly or completely closed. The chamber 50 of the chest 43 is in communication with the pneumatic or bellows 48 by means of a port 51, and

60 with the bellows chest, at the proper time, through a port 52. The upper or hinged side of the bellows 48 is connected with a regulating or control spring 53. A valve 54 controls the port 52 and said valve has a

65 stem connected with a flexible diaphragm 55,

which is secured at its edges upon the upper edges of a box or chest 56 which has a vent or bleed communication with the interior of the bellows chest 37, the purpose of which is to secure the balancing of the diaphragm

55. When the diaphragm 55 is dished downwardly, the valve 54 will close the port 52 and when the diaphragm is dished upwardly, the valve 54 will uncover the port 52, which is of greater diameter than the port 46. A conduit 58 leads from the chamber 40 of the action chest 39 to the chamber 50 of one chest 43 and a corresponding conduit 59 leads to the chamber 45 of the other chest 43. Both chests 43 are alike

75 80

and at each end of the main bellows chest 37 are the ports 46, 52, valve 54, diaphragm 55, box or chest 56 and vent or bleed 57. A conduit 60 leads within the chest 56 and below the diaphragm 55 at one end of the bellows chest 37 and a corresponding conduit 61 leads to the similar chest at the other end of the said bellows chest 37.

The conduits 24, 25 leading from the frame 20 and the conduits 60, 61 leading to the chests 56 inclosed within the bellows chest 37 are employed at their adjoining ends in connection with a stationary valve part 62 and a slidable valve part 63, the end portions of said valve parts having co-operating ports so arranged that the conduits 24, 60 may be placed in communication with each other and conduits 25, 61 may be placed in communication with each other, as will be understood from the following description.

95

The slidable valve part 63 may be moved to the left or right by means of a stem 64 and is held up against the stationary valve part 62 by means of springs 65 which are on screws 66 extending through slots in said movable part 63 and serving as guides and stops for the same. The stationary valve part 62 has ports 67 which are in direct communication with the conduits 60, 61, and also ports 68 which are in direct communication with the conduits 24, 25. The slidable valve part 63 has ports 69 and, on its upper side close against the stationary part 62, recesses or ports 70, and these ports 70 when the accenting mechanism is arranged for operation, connect the ports 68 and 67 so that communication is established from the conduits 24, 25 through the ports 68 and recesses 70 with the ports 67 which are in direct communication with the conduits 60, 61

105 110

leading into the boxes or chests 56 supporting the diaphragms 55, and it is this condition of the aforesaid ports that I illustrate in Fig. 1. When the accenting mechanism is not to be used, the slidable valve part 63 will, by means of the stem 64, be moved to the left, looking at Fig. 1, and this will have the effect of connecting the ports 67 with the ports 69 which are open to the atmosphere and cutting off commun- 115 120 125 130

cation through the recesses 70 between the ports 68 and ports 67. We may consider that the slidable valve part 63 is in the operative position shown for permitting the use of the accenting mechanism, and the description of the operation may be confined to say the bass side of the player, since that side is shown in section and also because the two sides of the player, while operating independently so far as the accenting is concerned, correspond exactly in construction and operation. During the soft playing or when notes are not to be accented, the parts will be in the relative positions in which they are represented in Fig. 1, but when one of the accenting perforations 19 in the music sheet passes into register with the opening 18 in the tracker-bar, and the opening 26 in the frame 20, atmospheric air passes through the said opening 26 and will pass through said frame to the conduit 24 and then through the ports 68, 70, 67 to the conduit 60, and thence to the lower side of the diaphragm 55 and result in the upward bulging of said diaphragm and the raising of the valve 54 from the port 52, at which time the exhaust in the bellows chest 37 will act through said port 52, it being of greater dimensions than the port 46, and through the port 51 to close the valve 49 and through the conduit 58 on the action chest 39, with the result of the exhaust acting more strongly at that moment on the note being played and accenting said note. The moment the perforation 19 in the music sheet, employed in accenting, passes the opening 18 in the tracker-bar, said opening 18 becomes closed at its front end, atmospheric air is cut off from the conduits 24, 60, and the valve 54 reseats upon the port 52 and then the exhaust action from the main bellows chest 37 is through the port 46, chamber 45, port 47, bellows 48, port 51 and chamber 50 on the conduit 58 and chamber 40 of the action chest 39.

What I claim as my invention and desire to secure by Letters-Patent, is:

1. In a musical instrument of the class described comprising a traveling music sheet having accenting perforations, a tracker-bar having an opening in position to register with said accenting perforations, an action chest, a main exhaust chest whose exhaust action on the action chest is modified to effect the accenting, and accenting mechanism for coöperative action with said music sheet and tracker bar and including controlling devices interposed between the tracker-bar and said main exhaust chest and comprising a hollow frame movable toward and from said sheet at the tracker-bar and having an opening in its rear face in position to register with the accenting perforations and to be opened thereby when said perforations, one after another, pass into register there-

with and with the opening in the tracker-bar, and a conduit for the passage of air at atmospheric pressure leading from said frame to the pneumatic mechanism.

2. In a musical instrument of the class described comprising a traveling music sheet having accenting perforations, a tracker-bar having openings in position to register with said accenting perforations, an action chest, a main exhaust chest whose exhaust action on the action chest is modified to effect the accenting, and accenting mechanism for coöperative action with said music sheet and tracker bar and including controlling devices interposed between the tracker-bar and said main exhaust chest and comprising a hollow frame movable toward and from said sheet at the tracker-bar and having independent air ducts in its opposite end portions and in the rear face of said portions openings in position to register with the accenting perforations and to be opened thereby when said perforations, one after another, pass into register therewith and with the openings in the tracker bar, and independent conduits for the passage of air at atmospheric pressure leading from the end portions of said frame to the pneumatic mechanism.

3. In a musical instrument of the class described comprising a traveling music sheet having accenting perforations, a tracker-bar having openings in position to register with said accenting perforations, an action chest, a main exhaust chest whose exhaust action on the action chest is modified to effect the accenting, and accenting mechanism for coöperative action with said music sheet and tracker-bar and including controlling devices interposed between the tracker-bar and said main exhaust chest and comprising a hollow frame movable toward and from said sheet at the tracker-bar and having independent air ducts in its opposite end portions and in the rear face of said portions openings in position to register with the accenting perforations and to be opened thereby when said perforations, one after another, pass into register therewith and with the openings in the tracker bar, and independent conduits for the passage of air at atmospheric pressure leading from the end portions of said frame to the pneumatic mechanism, said frame having means for adjusting its length to meet the requirements of the sheet and tracker bar.

4. In a musical instrument of the class described comprising a traveling music sheet having accenting perforations, a tracker-bar having openings in position to register with said accenting perforations, an action chest, a main exhaust chest whose exhaust action on the action chest is modified to effect the accenting, and accenting mechanism for coöperative action with said music

sheet and tracker bar and including controlling devices interposed between the tracker bar and said main exhaust chest and comprising a hollow frame movable toward and from said sheet at the tracker-bar and having independent air ducts in its opposite end portions and in the rear face of said portions openings in position to register with the accenting perforations and to be opened thereby when said perforations, one after another, pass into register therewith and with the openings in the tracker bar, independent conduits for the passage of air at atmospheric pressure leading from the end portions of said frame to the pneumatic mechanism, and a pneumatic for moving said frame to its operative and inoperative positions.

5. In a musical instrument of the class described comprising a traveling music sheet having accenting perforations, a tracker bar having openings in position to register with said accenting perforations, an action chest, a main exhaust chest whose exhaust action on the action chest is modified to effect the

accenting, and accenting mechanism for cooperative action with said music sheet and tracker bar and including controlling devices interposed between the tracker bar and said main exhaust chest and comprising a swiveled frame having side members and a connecting member extending when the frame is in operative position across said sheet along the tracker bar and said frame having openings in its rear face in position to register with the accenting perforations and to be opened thereby when said perforations, one after another, pass into register therewith and with the openings in the tracker bar, and independent conduits for the passage of air at atmospheric pressure leading from the end portions of said frame to the pneumatic mechanism.

Signed at New York city in the county of New York and State of New York, this 9th day of December, A. D. 1913.
